MUTE

Davis Shuman, Brooklyn, N. Y.

Application July 5, 1950, Serial No. 172,068

2 Claims. (Cl. 84—310)

1

The present invention relates to mutes for stringed instruments.

It has long been known that the tonal quality of a stringed instrument such as a violin, viola, cello, bass viol, guitar or the like can be changed or modified by damping the vibrations of the bridge by means of a mute. Mutes of various sizes and shapes have been used to obtain various degrees of damping, but all of the prior art mutes have been used to damp the bridge directly.

I have found that new and different effects can be obtained and the timbre and tone color of an instrument controlled to an amazing degree by muting or damping the vibration of a mute by the application of a second mute. When a mute is in place on a bridge, the attachment of a second mute to the first mute has a substantially different effect than attachment of the second mute directly to the bridge. Existing mutes are designed to be used alone and are not adapted to have other mutes attached to them, and to obtain the new effects it is essential that a new and different mute be provided.

One of the objects of the present invention is to provide a mute formed on its upper end to receive a second mute.

Another object is to provide a mute which may itself be muted.

A further object is to provide a mute having a variable muting capacity.

These and other objects and advantages reside in certain novel features of construction, arrangement and combination of parts as will hereinafter be more fully set forth and pointed out in the appended claims.

Referring to the drawing:

Figure 1 is a front elevation of a mute embodying my invention;

Figure 2 is a side elevation of the mute shown in Figure 1;

Figures 3, 4 and 5 are side elevations of modified forms of mute;

Figure 6 is a top plan view of the mute shown in Figure 5;

Figure 7 is a side elevation of a further modified form of mute;

Figure 8 is a front elevation showing a plurality of my mutes in place on the bridge of a stringed instrument;

Figure 9 is a front elevation of a further modified form of mute in place on the bridge of a stringed instrument;

Figure 10 is a section taken on line 10—10 of Figure 9; and

2

Figure 11 shows a portion of a violin with my mute in the keyhole slot of the tail piece.

The mute of my invention is shaped generally like mutes of the prior art and is applied to the bridge of an instrument in the same general way. In the embodiment shown in Figures 1 and 2 the mute comprises a body portion 10 having spaced legs or fingers 11. These legs or fingers 11 are spaced longitudinally to grip the front and back of the bridge 12 and are spaced transversely to grip the bridge 12 without interfering with the strings 13. Mutes have been made in a variety of shapes and sizes and with a variety of different forms of bridge gripping legs or fingers, and my mute can be made with almost any of these body shapes and gripping means.

The chief distinguishing feature of my mute is the formation of the top portion 14. A mute is ordinarily substantially thicker than the bridge so that the gripping legs or fingers will be longitudinally spaced sufficiently to grip the bridge, and the conventional mute has a body portion which is substantially the same thickness throughout. In my mute, the top portion 14 is thinner than the body portion 10 and is preferably of substantially the same thickness as the bridge. Because of this reduced top portion 14, a second mute can be placed on top of my mute and, if desired, a third mute placed on the second as shown in Figure 9. The top mute may be of conventional form or of my improved form since the top 14 of my mute has substantially the same shape as the bridge.

Figures 1 to 6 show several forms of my improved mute. In the form shown in Figures 1 and 2, the reduced top portion 14 extends along the middle of the body portion 10 and, in the modification shown in Figure 3, the reduced portion 14a extends along one side of the body. The reduced portion 14b of the modification shown in Figure 4 extends along one side of the body and is inclined toward the other side of the body while the reduced portion 14c shown in Figures 5 and 6 extends diagonally across the top of the body. While the body of my mute may be tapered in thickness to form the reduced upper portion, I prefer that the body form a definite shoulder at the bottom of the reduced portion to facilitate proper positioning of the second mute.

The modification shown in Figure 7, may be formed by fastening together two mutes of the type shown in Figure 3. This composite mute has two reduced portions 14a and may be fur-

ther muted by placing a mute on either or both of these reduced portions.

In the modification shown in Figures 9 and 10, a mute 15 which may be of the form shown in Figures 1 and 2 for example, has vertical channels 16 and 17 firmly secured to it. A second mute 18 is vertically slideable in the channels 16 and 17 with sufficient friction so that the mute 18 will stay in any selected position despite vibration of the bridge 12. In this modification, the mute 15 may be quickly damped or muted by pressing the mute 18 downward in the channels 16 and 17 until the fingers of mute 18 engage the reduced upper portion of mute 15.

The results with a single mute of the present invention is the usual, conventional tone quality. The use of two or more of my mutes as shown in Figure 8 for example, bring a richer and more pleasing quality of tone as well as a variety of tone colors never before heard from the standard stringed instrument used. This enables composers and music arrangers to use stringed instruments in a greater scope of blending with wind instruments when the mute is used in multiple augmentations. Soloists may also achieve a greater exploitation of a stringed instrument due to the new tone colors.

Any desired softness may be achieved by using a plurality of mutes and this softness is obtained without pitch distortion. Thus my mute permits practice in homes, hotels or apartments without disturbing neighbors.

Figure 11 illustrates another advantage of my mute. Heretofore musicians have carried mutes in their pockets since there was no convenient, readily accessible place on the instrument where the mute could be attached. Figure 11 shows a portion of a violin having a conventional body 20 and tail piece 21. The strings 13 are attached in the conventional keyhole slots 22 in the tail piece 21. The reduced upper end 14 of my mute is sufficiently thin to fit into a keyhole slot 22 in the tail piece 21 so that four of my mutes, one for each keyhole slot, may be fastened in the tail piece. The musician may thus have as many as four mutes in convenient location where they may be quickly applied to the bridge or to another mute.

From the foregoing it will be apparent that I am able to attain the objects of my invention and provide a new and improved mute for stringed instruments which is adapted to be further damped or muted to produce new and different tone color effects.

The invention may be embodied in other specific forms without departing from the spirit or essential characteristics thereof. The present embodiments are therefore to be considered in all respects illustrative and not restrictive, the scope of the invention being indicated by the appended claims rather than by the foregoing description, and all changes which come within the meaning and range of equivalency of the claims are therefore intended to be embraced therein.

What is claimed and desired to be secured by the United States Letters Patent is:

1. A mute for stringed instruments comprising a body portion of greater length than width and having a lower surface and flat upper surface, opposed fingers extending downwardly from the lower surface adjacent the opposite longitudinal edges thereof, and defining a longitudinal space of preselected uniform width, a supporting section extending upwardly from said flat upper surface, said supporting section being perpendicular to said flat upper surface, located intermediate the longitudinal edges thereof and being of uniform thickness equal to the width of said space between said opposed fingers.

2. A multiple mute for stringed instruments comprising, in combination, a mute according to claim 1 and at least one additional mute identical to said one mute, said additional mute being mounted on said one mute with the supporting section of said one mute disposed in frictional engagement between the spaced fingers of said additional mute.
